FEEDER FOR A BULLET LOADING MACHINE

Erwin S. Rodger, 58 Davis St.,
Locust Valley, N.Y. 11560

Filed Aug. 6, 1973, Ser. No. 386,214

Term of patent 14 years

Int. Cl. D15—99; D22—31

U.S. Cl. D22—99

FIG. 1

FIG. 2

FIG. 3

FIG. 4

FIG. 5

FIG. 6

FIG. 1 is a perspective view showing my new design for a feeder for a bullet loading machine;

FIG. 2 is a side elevational view thereof;

FIG. 3 is the opposite side elevational view thereof;

FIG. 4 is a front elevational view thereof;

FIG. 5 is a rear elevational view thereof; and

FIG. 6 is a bottom view thereof.

I claim:

The ornamental design for a feeder for a bullet loading machine, substantially as shown and described.
